U.S. Appl. No. 29/349,159, filed Mar. 12, 2010, Jason Patrick Shaw et al.

Primary Examiner — Carol P Rademaker

(57) CLAIM

The ornamental design for a bottle with closure, as shown and described.

DESCRIPTION

FIG. 1 is a top, front, and right side perspective view of a bottle with closure embodying our new design;
FIG. 2 is a front elevational view thereof;
FIG. 3 is a rear elevational view thereof;
FIG. 4 is a right side elevational view thereof, the left side elevational view being a mirror image;
FIG. 5 is a top plan view thereof; and,
FIG. 6 is a bottom plan view thereof.
